INVENTOR

BY Victor J. Evans

ATTORNEY

Lev Hayes

WITNESS:

UNITED STATES PATENT OFFICE.

WILLIAM P. MARTIN, OF MONGONGAHELA, PENNSYLVANIA.

BUMPER.

Application filed August 2, 1924. Serial No. 729,822.

To all whom it may concern:

Be it known that I, WILLIAM P. MARTIN, a citizen of the United States, residing at Monongahela, in the county of Washington and State of Pennsylvania, have invented new and useful Improvements in Bumpers, of which the following is a specification.

This invention relates to bumpers of the character used on automobiles, and contemporaneously 10 plates a structure designed to possess maximum strength and durability, and at the same time afford the desired resiliency or yieldability necessary in a device of this character.

15 The nature and advantages of the invention will be better understood when the following detailed description is read in connection with the accompanying drawings, the invention residing in the construction, combination and arrangement of parts as claimed.

20 In the drawings forming part of this application, like numerals of reference indicate similar parts in the several views, and

25 wherein:

Figure 1 is a front elevation of the bumper constructed in accordance with the present invention.

Figure 2 is a top plan view.

30 Figure 3 is a fragmentary detail view showing the connection between the respective sections of the rear bar.

Figure 4 is a sectional view taken on line

4-4 of Figure 2.

35 Figure 5 is a sectional view taken on line 5-5 of Figure 2.

The bumper forming the subject matter of the present invention is made up of three flat bars, and possesses the same general 40 outline of configuration of other bumpers in present day use. However the arrangement of the various bars is such as to give the bumper maximum strength and durability, without sacrificing the necessary resiliency or yieldability which a device of this kind should possess, in order to minimize injury to the bumper or object as the result of an impact between such parts. Referring to the drawing, 10 represents two front bars

45 which are arranged one above the other in spaced relation, the third or rear bar of the bumper being preferably made up of two parts indicated at 11 and 12 respectively and clearly shown in Figure 2. This sectional rear bar is adapted to be arranged in a plane 50 between the front bars 10, while the corre-

sponding outer extremities of all of the bars are connected together by knuckles of ordinary well known construction. In other words the outer ends of the front bars 10 60 terminate in loops 13, while the outer ends of the rear bar terminate to provide loops 14 which are arranged directly between and in a line with the loops 13 to receive the knuckle bolt 15.

65 Now, upon inspection of Figure 2 it will be observed that both sections of the rear bar are identical in construction, and each section is folded at an appropriate point in its length to provide a laterally and forwardly extended end portion 16 which terminates in the space between the front bars 10. These extremities of course constitute the adjacent inner extremities of the respective sections of the rear bar, and these sections are connected together by means of an inverted U-shaped element 17 secured to a base plate 18, each limb of the U-shaped member being received by the adjacent section of the rear bar as shown in Figures 2 70 and 3. The free extremities of the end portions 16 are arranged in the space between the front bars 10, and are held positioned therebetween by means of clamping plates 75 19 which are secured to the said extremity 80 by a bolt 20 as shown in Figure 5, the plates 19 being of a size to extend above and below the adjacent longitudinal edges of the front bars 10, and at opposite sides thereof. The plates 19 can be clamped to the bars 10 in 85 order to hold the end portions 16 of the sections of the rear bar fixed relatively to the front bars 10, or the plates 19 can be tightened to allow a slight sliding movement of the end portion 16 longitudinally of the bars 90 10, when the bumper comes in contact with an obstacle with sufficient force to cause the end portions 16 and the bars 10 to flex. The end portions 16 of the rear bar sections are arranged to materially strengthen the 95 bumper as a whole, and at the same time afford the bumper a maximum degree of 100 resiliency or yieldability.

105 While it is believed that from the foregoing description, the nature and advantages of the invention will be readily apparent, I desire to have it understood that I do not limit myself to what is herein shown and described, and that such changes may be resorted to when desired as fall 110 within the scope of what is claimed.

What I claim is:

1. A bumper of the character described comprising spaced upper and lower bars, and an intermediate sectional bar arranged rearwardly of the first mentioned bars, 25
5 means connecting the corresponding outer extremities of all of said bars, means for connecting the respective sections of the intermediate bar together, and means connecting the inner extremities of said sections 30
10 with said spaced bars.
2. A bumper of the character described comprising spaced upper and lower front bars, a sectional rear bar, means connecting the corresponding outer extremities of all of 35
15 said bars, said sections of the rear bar being folded upon themselves to provide oppositely extended inner end portions, and means connecting said end portion with said outer bars.
- 20 3. A bumper of the character described comprising spaced upper and lower front bars, a sectional rear bar, means connecting the corresponding outer extremities of all of said bars, said sections of the rear bar being 40
45 folded upon themselves to provide oppositely disposed inner end portions terminating in the space between the said front bars, means for securing said extremities to the front bars, and means connecting the respective sections of the rear bar together.

4. A bumper of the character described comprising spaced upper and lower front bars, a sectional rear bar, means for connecting the corresponding outer extremities of all of said bars, said sections of the rear bar being folded upon themselves to provide oppositely extended inner end portions terminating in the space between the front bars, 30
40 means including a U-shaped element straddling the respective sections of the rear bars and connecting said sections together, and means for holding the inner extremities of said sections positioned in the space between the front bars as and for the purpose specified.

In testimony whereof I affix my signature.

WILLIAM P. MARTIN.
